F. W. BECK AND E. W. SIEBERT, OF BALTIMORE, MARYLAND.

Letters Patent No. 71,684, dated December 3, 1867.

IMPROVEMENT IN MODE OF PACKING SMOKING-TOBACCO.

The Schedule referred to in these Letters Patent and making part of the same.

TO ALL WHOM IT MAY CONCERN:

Be it known that we, F. W. BECK and E. W. SIEBERT, of Baltimore, in the county of Baltimore, and State of Maryland, have invented a new and improved Manner of Packing Smoking-Tobacco; and we do hereby declare that the following is a full, clear, and exact description thereof, which will enable others skilled in the art to make and use the same, reference being had to the accompanying drawing, forming part of this specification.

The drawing represents a perspective view of our invention.

This invention relates to a new method of packing smoking-tobacco in such a manner that it may be in the most convenient form for consumers.

The invention consists in putting the ready-prepared and cut smoking-tobacco into small bags, of such size that they may be placed into the pocket of ordinary garments, said bags being closed by means of strings, which are drawn through the channels formed around their mouths. The bags will, in this form, answer as tobacco-pouches, which can be readily opened and closed, which can be carried by the consumer, and used until they are empty.

Heretofore, tobacco was packed for retail trade either in paper packages, or in woven bags, the latter consisting of one or more pieces sewed together. In none of these packages could the tobacco be retained to be carried in the consumer's pocket after the packages were once opened, as they could not be again securely closed. By packing the tobacco at once in pouches which can be opened and closed at will, it is brought into the most practical form for consumers.

A represents a bag or pouch, hemmed around its mouth so as to form a channel for the admission of the cord B, by means of which the bag can be closed or opened at will. The size of the bag is such that it can be conveniently carried in the pocket, it being adapted to hold from about one-eighth to one-half or a whole pound of tobacco.

The tobacco is placed into the bag, and is pressed, so as to completely fill the same. The bag is then closed and the string is tied, its ends being covered with a seal or label to prevent the fraudulent opening of the bag. The tobacco is sold in these bags, and, when the same are opened, they can again be closed, and the tobacco can consequently be gradually taken from the bag as it is being used.

Instead of hemming around the mouth of the bag, the string may be drawn directly through the body of the bag in a well-known manner.

We do not claim placing tobacco into bags, as that has already been done, such bags being closed by seams on all sides; but we do claim as new, and desire to secure by Letters Patent—

As a new article of manufacture, a package of cut smoking-tobacco, the envelope of which is a cloth bag constructed, as described, so that it can be opened and closed at pleasure, in the manner and for the purpose specified.

F. W. BECK,
E. W. SIEBERT.
